UNITED STATES PATENT OFFICE.

HUGO F. LIEDTKE, OF HAGERSTOWN, MARYLAND, ASSIGNOR TO PANGBORN CORPORATION, OF HAGERSTOWN, MARYLAND, A CORPORATION OF MARYLAND.

SAND-BLAST APPARATUS.

1,423,128.

Specification of Letters Patent. Patented July 18, 1922.

Application filed December 8, 1920. Serial No. 429,233.

To all whom it may concern:

Be it known that I, HUGO F. LIEDTKE, a citizen of the United States, and resident of Hagerstown, Maryland, have invented certain new and useful Improvements in Sand-Blast Apparatus, of which the following is a specification.

My invention relates to sand blast apparatus for cleaning castings or like purposes, of the type in which a sand blast nozzle is movably mounted in a chamber or cabinet into which the castings or articles to be treated by the sand blast are transported by a movable carrier which also effects their delivery from the sand blast chamber. The invention is shown in the accompanying drawings, in which—

Figure 1 is a central vertical sectional view through the apparatus, the sand blast gun being omitted.

Fig. 2 is a front elevation of the apparatus.

Fig. 3 is a plan view partly in section.

Fig. 4 is a view of the sand blast gun and its support.

The apparatus comprises a chamber A in which is located a sand blast gun 1. At the lower part of this chamber there is a rotary table which projects partly into the chamber and partly extends outside of the same. This table 2 has a deep flange 3 and carries gratings 4 through the openings of which the sand may pass, and upon which the castings are supported while being transported into and out from the chamber A. An inspection door is provided at 5 through which the operator may make adjustments or replacements. This chamber is lined with heavy wear plates 6 to prevent the sand from causing undue wear on the casing. These plates are removable to be replaced by new plates when worn. The rotary table is cast in one piece and the deep flange 3 prevents the blast from blowing smaller and lighter articles off from the same. The table is mounted by its hub 7 upon a central vertical shaft 8 by which it is rotated. The front projecting portion of the table is protected by a guard 9 which is provided with a bottom plate 10 over which scrapers 11 move, the latter being secured to the bottom of the rotary table and serving to scrape the sand from the bottom plate 10 of the guard into the hopper 12. At the rear portion of the table is located a guard 13, this being formed

in sections and covering the space between the upstanding flange of the table and the casing 14, and this guard prevents any of the work pieces from dropping into the hopper 12 and causing a jam of the table 60 and clogging the flow of the sand therefrom. A baffle cylinder 15 is bolted to the vertical shaft 8 and covers and protects the hub of the table and prevents the abrasive material from acting thereon or from flying outwardly from the table. The vertical shaft 8 finds a bearing at its lower end at 16 and at its upper end it turns in a bearing 17. It is provided with a worm wheel 18 at its upper end driven by a worm 19 on a shaft 70 20 mounted in suitable bearings, said shaft having at one end a spur gear 21 meshing with a pinion 22 on a shaft 23 having a crank 24. This shaft is mounted at its inner end in a bearing 25 and at its outer end in 75 a bearing 26, the latter being secured to the casing. This crank shaft is pulley driven, a tight and loose pulley being provided thereon at 27 and a belt shifting fork being provided at 28. This crank shaft gives motion to the sand blast gun through the following mechanism:

A rod or link 29 is pivotally connected at 30 to a member carried by the crank and the other end of this link is pivoted at 31 85 to a bracket or member 32 swivelled on a swinging arm or lever 33, mounted on the upper end of a shaft 34 which turns in bearings 35. The arm or lever 33 is thus adapted to swing in a horizontal plane under the 90 action of the back and forth movement imparted from the crank through the link or rod 29, and this horizontal swinging motion of the vertical shaft 34 is communicated to the sand blast gun by an arm 36 supported 95 in a bracket 37 adjustably fixed to the vertical shaft 34. This rod 36 is provided with a holder or bracket 38 for the sand gun which depends therefrom at a slight angle to a vertical line. To the holder or bracket 100 38 is attached the compressed air supply hose 39 and it also has screwed into it an air jet 40 which delivers the air to the blast gun. The blast gun 1 is held in place by means of the set screw 41 which clamps it 105 to the air jet tube. A suction hose 42 is connected to the blast gun body and through this hose the sand is delivered to the blast gun. A nozzle 43 is connected to the body 110 of the blast gun by a set screw 41 and

through this the blast of sand is delivered and directed upon the articles carried by the table. The suction hose 42 as well as the compressed air hose leads from the outer 5 wall of the chamber A and by means of suitable connections 39, 42 they are joined to the air and sand supply lines.

At the lower end of the hopper 12 there is provided a sand feed box 44 and the suction supply hose 42' leads from this box 10 to receive its supply of sand therefrom. The compressed air line is provided with a globe valve 45 and a pressure gauge 46. A suitable clean-out door 47 is provided in the 15 wall of the hopper.

It will be observed that the vertical shaft 8 and the driving mechanism are located in a compartment divided off from the blast chamber A. Any number of rows of 20 flexible flaps 48 may be provided to close the opening through which the table rotates, so that the abrasive material will not be discharged from the chamber A to the outside. In the operation of the apparatus the 25 belt is applied to the tight pulley. Abrasive material is then supplied by dumping it onto the front projecting portion of the table. This abrasive material drops from the 30 perforated grates and is carried by the scrapers on the bottom of the table, into the hopper and after a sufficient amount of abrasive has been supplied, the castings or other articles to be cleaned are placed on the outer projecting portion of the table 35 and the air valve is then opened. The air under pressure issuing from the air jet tube creates a partial vacuum in the blast gun body and thus draws a mixture of air and sand from the bottom of the hopper at 40 which the sand feed box is located. This mixture, together with the air from the air jet 40, is projected through the nozzle onto the work pieces to be cleaned, and during the cleaning operation the blast gun is oscillated in a horizontal plane, due to the rocking motion imparted to the vertical shaft 34 from the crank shaft through the connections above described. This will cause 45 the blast to traverse the rear portion of the table surface to act upon the articles held thereon and being transported thereby, so that these will be thoroughly cleaned. The nozzle can be raised or lowered, depending upon the class of work to be cleaned, by 50 adjusting the bracket or casting 37 up or down on the shaft 34. In order to allow any generated dust to escape, a ventilating opening is provided at 49 and a draft of air is induced through the flexible flaps into the 55 blast chamber A and thence out through the ventilating opening 49. The abrasive which is discharged through the nozzle onto the castings or articles for performing the 60 cleaning action thereon flows through the perforations in the gratings carried by the 65 rotating table and then lodges in the hopper 12 for use over and over again.

The connection between the crank shaft and horizontally oscillating lever 33 is of a universal character by reason of the swivel members carried 70 respectively by the crank pin and the arm 33 and by reason of the pivoted connections between the link or rod 29 and these members.

The throw of the blast gun or the length 75 of its oscillating movements may be varied by adjusting the member 32 on the horizontally moving lever 33, for which purpose collars 50 are adjustably held by set screws on the lever 33.

I claim:

1. In combination in a sand blast apparatus, a casing, a rotary carrier lying partly within and partly without said casing, a sand blast nozzle, an air jet nozzle, 85 an arm supporting said nozzles at its free end and oscillating in a horizontal plane over the said table, a vertical shaft carrying said arm, and a pair of flexible hose pipes extending from a point adjacent the axis of 90 oscillation of the said nozzle supporting arm to the nozzles carried thereby, substantially as described.

2. In combination in a sand blast apparatus, a casing, a rotary carrier lying 95 partly within and partly without said casing, a sand blast nozzle, an air jet nozzle, an arm supporting said nozzles at its free end, and oscillating in a horizontal plane over the said table, a vertical shaft carrying 100 said arm, and a pair of flexible hose pipes extending from a point adjacent the axis of oscillation of the said nozzle supporting arm to the nozzles carried thereby, a receiving hopper below the rotary table, a pipe extending from the lower end of the receiving hopper and connected with the oscillating sand hose at its upper end, a fitting connected with the oscillating air hose and a pipe to supply air to said fitting and hose, 110 substantially as described.

3. In combination, a casing, a carrier for the work pieces, a vertical shaft for driving said carrier, a horizontal drive shaft at the upper part of the casing, a connection from the said horizontal drive shaft to the vertical shaft for rotating the carrier, said drive shaft having a crank, a nozzle supporting arm arranged to oscillate in a horizontal plane within the casing, a vertical shaft carrying said nozzle supporting arm, a horizontal arm on said vertical shaft, and a link connection between the last mentioned arm and the crank of the horizontal driving shaft, substantially as described.

4. In combination, a casing, a carrier for the work pieces, a vertical shaft for driving said carrier; a horizontal drive shaft at the upper part of the casing, a connection from the said horizontal drive shaft to the 130

vertical shaft, said drive shaft having a crank, a nozzle supporting arm arranged to oscillate in a horizontal plane within the casing, a vertical shaft carrying said nozzle

whereby the latter joint is adjustable along the arm to provide for different lengths of oscillating strokes of the gun carrying arm, substantially as described.

50

5 supporting arm, a horizontal arm on said vertical shaft, and a link connection between the last mentioned arm and the crank of the driving shaft, said connection having a universal joint between its ends and the said 10 arm and crank respectively, substantially as described.

8. In combination in apparatus of the class described, a rotary table, a casing, an arm oscillating in a horizontal plane over

15 the table, a bracket mounted on the free end of the arm, an air nozzle carried by the

55

bracket and projecting therefrom a sand blast gun supported on and surrounding

20 said nozzle, and having a nozzle in line with the air nozzle, and a pair of flexible

60

hose pipes, one of which connects with the

25 bracket to supply air to the air nozzle and

65

the other of which connects with the gun,

30 both of said flexible hose pipes extending from a point adjacent the vertical axis about which the said arm oscillates, substantially

65

as described.

9. In combination, a rotary table, a casing, a carrier lying partly within and partly without said casing, a vertical shaft for driving the

70

15 carrier, a worm wheel at the upper part of

35 said shaft, a worm for driving said wheel, a horizontal driving shaft geared to the

worm shaft and having a crank, means for

20 operating the horizontal drive shaft, a hori-

zontally movable arm, a nozzle supported at

the free end thereof, a vertical shaft carrying

the said arm, and a connection between

the crank shaft and the vertical shaft, sub-

stantially as described.

10. In combination, a casing, a rotary carrier having removable perforated supports for the work pieces, scrapers on the under side of the said carrier independent of the removable perforated supports, a bot-

75

30 tom plate for receiving the sand passing

through the perforations, a hopper into

35 which the scrapers deliver the sand, a sand

blast nozzle within the casing directed to-

wards the surface of the carrier, and means

40 for delivering sand to the said nozzle, sub-

stantially as described.

7. In combination, a rotary table for hold-

ing the articles to be treated, a casing, a sand

blast gun, an arm carrying the same at

45 its free end, a vertical shaft upon which

said arm is mounted, means for oscillating

the said shaft consisting of an arm 33 there-

40 on, a horizontal drive shaft, having a crank,

a link having a universal joint connection

45 with the crank, and having a universal joint

connection with the arm 33, and means

10. In combination, a rotary table, an arm

oscillating horizontally thereover, a vertical

shaft carrying said arm and along which

said arm is adjustable towards and from the

table, a sand blast gun on the free end of the

arm, a casing enclosing the arm and a part

of the table, flexible air and sand hose ex-

80 tending from the sand blast gun along the

oscillating arm to a point adjacent the verti-

cal shaft, fittings to which the said air and

sand hoses are connected and pipes for de-

85 livering sand and air to said fittings, sub-

stantially as described.

In testimony whereof, I affix my signature.

HUGO F. LIEDTKE.
